UNITED STATES PATENT OFFICE.

JOHN H. ALLEN, OF BROOKLYN, NEW YORK.

JOURNAL-BOX.

SPECIFICATION forming part of Letters Patent No. 236,868, dated January 25, 1881.

Application filed November 18, 1880. (No model.)

To all whom it may concern:

Be it known that I, JOHN H. ALLEN, of Brooklyn, in the State of New York, have invented a new and Improved Journal-Box, of 5 which the following is a specification.

Figure I is a sectional elevation and partly front view. Fig. II is partly a top view and one-half in section at center of shaft.

Similar letters of reference indicate corresponding parts.

This invention, which is more particularly intended for pillow-blocks cast upon the bed-plate of the engine, consists in making the wedges on each side, which act against the 15 side cheeks, to extend the whole length of the cheeks or the whole length of the bearing, with straight surfaces at their inner side, next to the cheeks, and with cylindrical outer surfaces fitting into cylindrical surfaces of the pillow-block jaws, whereby the journal-boxes, together with the wedges, can turn in the pillow-block, if, at any time, the shaft should come 20 out of line.

In the drawings, G G represent the jaws of 25 the pillow-block. The inner surfaces of these jaws are made cylindrical and inclined, into and against which the side wedges, H H, are fitted.

The journal-box is composed of an upper 30 piece, m, lower piece, n, and side piece or bearings, w w. A suitable cap, K, confines the journal-boxes. The upper piece, m, and lower piece, n, are fitted square upon the bottom of

the pillow-block and against the under side of the cap K.

The keys or wedges H H are made cylindrical on their outside, and placed in contact with the inclined and cylindrical surfaces of the jaws G G, while their straight surfaces are placed in contact with the straight outer surfaces of the side pieces, w w. The wedges H H are moved by means of suitable screws J J passing through the cap K, and by this means 35 adjust the side pieces, w w. By this arrangement and construction of making the outside 40 of the wedges H H inclined and concentric, fitting against corresponding surfaces in the jaws G G, an equal bearing is obtained against the side pieces, w w, in their whole length, and consequently these side pieces or bearings, w 45 w, can be made to bear evenly against the 50 whole length of the journal of the shaft, even if said shaft should be slightly out of line.

What I claim as my invention, and desire 55 to secure by Letters Patent, is—

In combination with the side pieces or side bearings, w w, of a journal-box, the wedges H H, provided with concentric inclined outer surfaces fitting against corresponding surfaces in the inside of the pillow-block jaws G G, ar- 60 ranged in the manner and for the purpose substantially as described.

JNO. H. ALLEN.
